[57] CLAIM

The ornamental design for an expandable culinary finger dicing guard, as shown and described.

DESCRIPTION

FIG. 1 is top, front, and left side perspective view of an expandable culinary finger dicing guard showing an attached second expandable culinary finger dicing guard in phantom; FIG. 2 is a top plan view thereof; FIG. 3 is a bottom plan view thereof; FIG. 4 is a right side elevational view thereof; FIG. 5 is a front elevational view thereof. FIG. 6 is a rear elevational view thereof.

FIG. 7 is a top, front, and left side perspective view of an expandable culinary finger dicing guard showing my novel design; FIG. 8 is a top plan view thereof; FIG. 9 is a bottom plan view thereof; FIG. 10 is a right side elevational view thereof; FIG. 11 is a left side elevational view thereof; FIG. 12 is a front elevational view thereof; and, FIG. 13 is a rear elevational view thereof.

The broken line showing of the guard is for illustrative purposes only and forms no part of the claimed design.
